UNITED STATES PATENT OFFICE.

JOHN PRIMROSE, OF NEW YORK, N. Y.

OIL-STILL.

1,389,978.

Specification of Letters Patent. Patented Sept. 6, 1921.

Application filed June 5, 1920. Serial No. 386,733.

To all whom it may concern:

Be it known that I, JOHN PRIMROSE, a citizen of the United States of America, residing at New York, in the county and State of New York; have invented certain new and useful Improvements in Oil-Stills, of which the following is a full, clear, and exact description.

In certain forms of oil stills by the use 10 and operation of which what is known as fractional distillation is practised provision is made for subjecting the oil in successive banks of tubes or heating surface to a gradually increasing temperature and for taking 15 off the vapor formed in each bank and passing the unvaporized oil on to the next bank. In such stills, in order that the circulation of the oil may be effected by a single pump, it is important to control the pressure be- 20 tween each bank of heating surface but this is a problem by no means easy of practical solution.

I have, however, devised a means for accomplishing this which meets all practical 25 requirements and this means is made the subject of my present application for Letters Patent. According to this my invention I install a pressure control chamber between each bank of heating surface and provide in 30 such chamber a float valve of special construction which controls the gas outlet of the chamber, closing it when the oil in the chamber backs up by reason of any obstruction in the next succeeding bank of heating 35 surface and rises to or beyond a predetermined level. By this means the pressure in the closed control chamber rises until it is sufficient to overcome and remove the obstruction, whereupon the level of the oil 40 falls, the gas outlet is again opened and the gas released.

The apparatus which I have designed for this purpose is illustrated in the accompanying drawings, in which:

45 Figure 1 is a vertical sectional view of a still embodying my improvements taken on the line 1—1 of Fig. 2, and

Fig. 2 is a longitudinal section and part elevation of the complete still.

50 The special character and construction of the still are not of the essence of this invention and may be greatly and widely varied provided it exhibit the essential characteristics hereinafter set forth. That 55 shown comprises a furnace or fire box 1 in the top wall 2 of which composed of heat-

resisting material a single zig-zag line 4 of pipes conveys the cold oil from the source 3 to the banks of tubes or heating surfaces placed above the said top partition 2 and exposed to the current of hot gases from the fire box.

Primarily the oil receiving its initial heat in the pipes 4 is carried to the first bank of heating surface 5 and after passing through this in series it passes successively to and through the succeeding banks 6, 7 and 8. The flow of oil is counter to the flow of the hot gases, the last bank of the series 8 being in position to be swept by the hottest gases, and in practice the extent of the heat-absorbing surfaces will be in inverse proportion to the temperature of the gases impinging thereon.

In each stage of such a still vapors are driven off, and it is desirable that they be collected and separately stored by reason of their different character. I therefore conduct the oil after passing through the series of pipes 4 to a separator from which such vapor as is set free is taken off, while the oil is then passed on to the first bank of heating surface 5 and then led to a second separator and so on throughout the whole series.

The separators and the pressure control chambers are all of substantially the same construction, and only one need be described in detail. I have therefore shown in Fig. 1 the separator 9 connected between the banks 5 and 6 for purpose of illustration.

The oil from the first separator 10 is led by a pipe 11 to the bottom of the bank 5 and from the top of the same bank by a pipe 12 to the top of the separator 9. The construction of this latter device is largely immaterial to the present invention. The hot oil is delivered onto a spreader 13 and falls into a conical receiver 14 from which it passes onto another spreader, and so on. Beneath the conical receivers are gas chambers from which lead gas outlets 15 which connect with a gas pipe 16, the upper end of which connects with the upper space of the separator. By this device the vapors dissociated from the oil are led off into the top of a pressure control chamber 17, the lower part of which is connected by a pipe 18 with the lower part of the separator.

The tapered bottom of the latter connects by a pipe 19 with the lower row of tubes in the next bank 6, and the oil which finds its

way down through the separator is forced by the pressure on through the series of banks, as will be understood.

- Should any stoppage of this flow occur in 5 any succeeding bank of tubes, then oil will back up in the chamber 17 and its level will rise, not only in the separator but in the chamber 17, and this rise of level is taken advantage of to shut off the gas outlet.
- 10 For this purpose a float valve 20 is used in chamber 17 which carries a perforated brass tube 22 constituting the gas outlet. As long as the level of oil in chamber 17 is below a certain line the gas entering the chamber 15 finds its way off through the perforators and the tube 21 into the outlet tube 22, but should this level rise a certain and predetermined amount, the outlet is closed, and the pressure therefore accumulates in chamber 20 17 until it becomes sufficient to force on any impediment to its flow through the next bank. As soon as the passage is thus cleared the oil level falls, the valve 20 opens the outlet and the operation proceeds as 25 before.

It will be observed that such gas as forms in the pipes 4 is taken off by the separator 10, that which forms in the first bank 5 is taken off from the separator 9 and so on, 30 there being a separator and a pressure control chamber associated therewith, for each of the groups of heating surfaces. Pressure from a single source, therefore, which drives the oil into the still suffices to carry 35 the unvolatilized oil completely through the entire still, and the operation is thereby greatly simplified and improved.

What I claim is:—

1. In an oil still comprising a plurality of

heating surfaces in which the oil is subjected to varying effects of the furnace temperature, the combination of liquid and vapor separators with and intermediate to adjacent heating surfaces, and a control device connected with the vapor outlet of each of said separators and means therein for closing such outlet when the oil backing up therein by reason of a stoppage in its flow reaches a predetermined level.

2. In an oil still comprising a plurality of heating surfaces in which the oil is subjected to varying effects of the furnace temperature, the combination of liquid and vapor separators with and intermediate each two adjacent heating surfaces, a chamber connected with each separator for receiving the vapor therefrom and a controlling valve for closing the outlets from said chambers adapted to be operated by a stoppage of the flow of oil through the next succeeding heating surface and a predetermined rise of the level thereof.

3. In an oil still comprising a plurality of banks of heating surfaces for oil placed in different relations to the flow of hot gases from the furnace, the combination of liquid and vapor separators with and intermediate each two adjacent banks, chambers connected with said separators for receiving the gas therefrom, outlets for said chambers, connections between the chambers and the separators and a float valve in each chamber which closes the outlet when by reason of a stoppage of flow the oil in said chamber rises to a predetermined level.

In testimony whereof I hereto affix my signature.

JOHN PRIMROSE.
